UNITED STATES PATENT OFFICE.

HENRY L. DISMER, OF DAVENPORT, IOWA.

MACHINE FOR WRAPPING BED MATTRESSES.

Application filed March 16, 1925. Serial No. 16,077.

To all whom it may concern:

Be it known that HENRY L. DISMER, a citizen of the United States, residing at Davenport, in the county of Scott and State 5 of Iowa, has invented certain new and useful Improvements in Machines for Wrapping Bed Mattresses, of which the following is a specification.

My invention relates to improvements in 10 machines for wrapping bed mattresses and similar bulky objects.

The objects of my invention are to provide a simple mechanically constructed and 15 easily operable machine for holding and wrapping mattresses, with means to permit the easy removal thereof after being wrapped and tied.

I attain these objects by the mechanism 20 illustrated in the accompanying drawings, in which,—

Figure 1 is a plan view; Fig. 2 is a side elevation thereof; Fig. 3 is an enlarged sectional detail showing the fastening of the bed sheets to the angle irons; Fig. 4 is a 25 detail of the main shaft and Figure 5 is an enlarged detail in cross section of the movable main shaft bearing on the line 3—3 of Figure 2.

My machine comprises a bed composed 30 preferably of metal sheets, 10, 11 and 12, secured to angle irons, 2, 4, 5, 6, 7 and 8, supported at the foot by legs, 1 and 3, preferably composed of angle iron and stiffened by diagonal braces, 48.

The head of the bed is supported by a 35 frame preferably composed of angle iron, with oblique upright legs, 13, 16, 17, 20, 24 and 28. The legs, 13 and 16, are stiffened by diagonal braces, 14 and 15, and the legs, 17 and 20, are stiffened by diagonal braces, 49 and 50.

A lateral brace, 48^a, has one end secured 40 to cross braces, 49 and 50, and its middle portion secured to the rib, 22, which with the angle irons 9, 21 and 23, support the curved end of the bed and its opposite end secured to the corresponding cross braces 45 secured to the legs, 13 and 20.

The bed of my machine has a substantially 50 horizontal portion extending from the foot supports to the main supports and a regularly curved bed, 51, extending upwardly from that point to the highest point of the bed. The thin metal sheets which form 55 the bed are preferably secured to the angle

irons by countersunk screws or bolts as shown in Figure 3, so as to leave a smooth surface upon which nothing can catch.

A main shaft, 33, is mounted in bearings, 60 32, 34 and 41, and each of these bearings is formed with a downwardly extending portion which is secured to the adjacent portion of the angle irons forming the upper portion of the legs of the main frame. One 65 end of the shaft has secured to it a crank, 30, which is secured by a set screw, 31, and is provided with a handle, 29, by which the shaft can be turned manually.

Arms, 35 and 40, formed integral with 70 hubs, are mounted upon the shaft over the curved portion of the bed. An auxiliary shaft, 39, is mounted in the arms, 35 and 40, one end of which being secured to the arm, 35, by lock nuts, 37 and 38, and the opposite 75 end being seated in a suitable opening in the outer end of the arm, 40. The arm, 40, has an enlarged hub formed integral therewith, which extends outwardly from the body of the machine and this hub has an 80 opening corresponding to the free end of the shaft, which has its upper half cut away as in Figure 4.

The bearing, 41, is secured by bolts, 44, 85 to the upper end of the angle irons forming the legs, 28 and 24, and is hinged to the lower portion of the legs by a rod, 25, so that it can be placed in a vertical position as shown in Figure 2, or in a horizontal position as shown in dotted lines in Figure 1. 90

In the operation of my device, the sheet of paper or material with which the mattress is to be wrapped is first spread upon the bed, 12, and the mattress laid thereon with the upper end of the mattress and 95 paper extending between the main shaft, 33, and the auxiliary shaft, 39, the auxiliary shaft securing them in position. By turning the crank, 30, the main shaft, 33, is revolved and the mattress and paper wound 100 thereon and then securely tied.

The arm, 40, and its supporting angle irons, 26 and 27, are then swung outwardly and downwardly upon the rod, 25, as a pivot, so as to leave one end of the main shaft 105 and the corresponding end of the auxiliary shaft free. The rolled mattress can then be slid off the main shaft and the auxiliary shaft laterally and the machine will then be ready to insert a new mattress and repeat the operation. 110

The bearings, 32 and 34, should be spaced

far enough apart to afford a firm support for the free end of the main shaft when disengaged from its bearing, 41.

I claim:

5. 1. A machine for folding and wrapping mattresses comprising a bed, an extended fixed support secured to the bed, at one side thereof carrying a pair of widely spaced bearings secured thereto, and a relatively 10 narrow hinged support secured to the opposite side thereof, the hinged portion of said support carrying a suitable bearing, a head having an arm formed integral therewith revolvably mounted in the bearing 15 of the hinged support, a main shaft having one end rotatably mounted in the bearings of the fixed support and its opposite end adapted to enter the head secured in the bearing of the hinged support when in vertical position, a fixed arm secured to the main shaft adjacent the fixed bearings thereof, an auxiliary shaft having one end secured in the fixed arm and its opposite end adapted to enter the arm of the head secured in the hinged bearings and means for 20 rotating the main shaft secured near the fixed bearings thereof.
2. A machine for folding and wrapping mattresses comprising a flat bed mounted 25 adjacent a curved head, an extended fixed support secured to the bed and curved head at one side thereof carrying a pair of widely spaced bearings secured thereto, and a rela-

tively narrow hinged support secured to the opposite side thereof, the hinged portion of 35 said support carrying a suitable bearing, a head having an arm formed integral therewith revolvably mounted in the bearing of the hinged support, a main shaft having one end rotatably mounted in the bearings of the 40 fixed support and its opposite end adapted to enter the head secured in the bearing of the hinged support when in vertical position, means secured to the main shaft adapted to hold one end of a mattress in engagement 45 with the main shaft while being wrapped.

3. A machine for folding and wrapping mattresses comprising a flat bed mounted adjacent a curved head, an extended fixed support secured to the bed and curved head 50 at one side thereof carrying a pair of widely spaced bearings secured thereto, and a suitable support secured to the opposite side thereof, a main shaft having one end rotatably mounted in the bearings of the fixed support and means by which the opposite end of the main shaft can be supported while wrapping a mattress and left free when the wrapping is completed, means secured to the main shaft adapted to hold one end of 55 a mattress in engagement with the main shaft while being wrapped.

In testimony wherof he affixes his signature.

HENRY L. DISMER.
